UNITED STATES PATENT OFFICE.

AMOS L. FOREMAN, OF BALTIMORE, MARYLAND, ASSIGNOR TO FOREMAN'S SYSTEMS,
INCORPORATED, OF WILMINGTON, DELAWARE, A CORPORATION OF DELAWARE.

BOTTLE-CRATE.

1,340,881.

Specification of Letters Patent.

Patented May 25, 1920.

Application filed November 13, 1916. Serial No. 131,121.

To all whom it may concern:

Be it known that I, AMOS L. FOREMAN, a citizen of the United States, residing in Baltimore, Maryland, have invented certain 5 Improvements in Bottle-Crates, of which the following is a specification.

My invention consists of certain improvements in the bottle crate forming the subject of my previous Letters Patent No. 1,050,823, 10 dated January 21, 1918, the object of my present invention being to securely connect the ends of the longitudinal bottle-separating strips to the end members of the crate without the use of nails.

15 This object I attain in the manner herein-after set forth, reference being had to the accompanying drawings, in which—

Figure 1 is a longitudinal vertical section of a bottle crate constructed in accordance 20 with my present invention;

Fig. 2 is a transverse vertical section of the same;

Fig. 3 is a vertical sectional view, on a larger scale than Fig. 1, of part of one of 25 the end members of the crate and of the connection between the same and an end of one of the longitudinal strips;

Fig. 4 is a vertical section, on a larger scale than Fig. 2, of side members of the 30 crate and of the connection between the same and an end of one of the transverse strips;

Fig. 5 is a perspective view, on the same scale as Fig. 3, of an end portion of one of the longitudinal strips;

35 Fig. 6 is a similar perspective view illustrating a modification;

Fig. 7 is a top view of one corner of the crate and of the corner plate applied thereto;

40 Fig. 8 is a bottom view of said corner and of the bottom plate applied thereto;

Fig. 9 is a view, partly in elevation and partly in vertical section, on the line 9—9, Fig. 7; and

45 Fig. 10 is a horizontal section on the line 10—10, Fig. 9.

The frame of the crate is composed as before of end members 1, bottom end strips 2, and side members 3 and 4, and the bottle 50 supporting and separating structure of the crate comprises the bottom wire 9^a, the longitudinal separators 11 and the transverse separators 12.

The crate may be constructed for the reception of any desired number of bottles, de-

pending upon the number of strips 11 and 12 employed.

The bottom wire 9^a is carried back and forth between the bottom end strips 2 and is let into recesses in the tops of said strips, 60 the ends of the longitudinal separators 11 are secured to the ends 1 of the crate and the ends of the transverse separators 12 fit between and are secured to the side members 3 and 4. The securing devices for the ends 65 of the separators 11 and 12 are, however, of a different character from those employed in the former crate, being intended to provide a more secure connection than before between the separators and the end and side 70 members of the crate and to dispense with the use of nails in effecting such connections.

The ends of the flat strips from which the longitudinal separators 11 are made form split tubes 5 which pass through openings 75 formed in the end members 1 and terminate in the countersunk ends 6 of said openings, the outer end portions of each member 5 being flanged down upon the outer face of a washer 7 which surrounds said member 5 80 and bears with its inner face against the base of the countersunk outer end 6 of the opening in the end member 1 through which the end member 5 passes, the flanged outer end of said member 5 being within the countersink 6 so that said end member 1 presents a smooth outer face. Instead of being in the form of split tubes the opposite ends of the separators 11 may be pressed or forged 85 into solid rod-like form, as shown for instance at 5^a in Fig. 6, the outer end of the rod-like member in this case being riveted down against the outer face of the washer 7. In either case the ends of the longitudinal 90 separators 11 will be securely confined to the end members 1 of the crate without the use of nails and without weakening the end portions of the separators by forming therein openings for the reception of said nails.

For the sake of economy it is frequently 100 advisable to build up the end members 1 of the crate from two or more relatively narrow pieces, and I find that this can be done without materially weakening the end member if said component parts of the latter are 105 locked together by means of dowels 8 with notched edges 8^a, such as shown in Figs. 1 and 3.

This, however, forms no part of my present invention.

The side members 3 and 4 of the crate are likewise locked together, as shown in Fig. 4, by dowels 13, which also pass through openings in the strips from which the transverse bottle separators 12 are made, and thus serve to firmly secure the latter to the side members 3 and 4. The dowels 13, are preferably in the form of circular pins with tapered ends and side notches forming shoulders 13^a for engagement with the wood of the side strips 3 and 4, as shown in Fig. 4.

The edges of the pieces of wood may have formed in them, for the reception of the pins, openings of less diameter than said pins but in most cases this has been found to be unnecessary.

At each corner of the crate there is an angular top plate 14 and an angular bottom plate 15 conforming to the side and end members of the crate and secured thereto by nails 16, although screws may be used instead of nails, if desired. The top member 14 has a downwardly projecting flange 14^a for engagement with the inner faces of the end and side members of the crate, and an upwardly projecting flange 14^b for engaging with the corners of a crate above it, and insuring the proper centering of the crates when they are piled one upon another.

The top and bottom corner plates 14 and 15 are tied together by means of a rod 17 which is contained in a mortise formed in the end member 1 of the crate in line with one of the faces of the rabbet joint between said end member of the crate and the side member, so that it can be readily produced at the same time that the end member is being rabbeted.

The ends of the rod 17 pass through countersunk openings in the top and bottom plates 14 and 15 and are in rigid engagement therewith, so as to firmly tie the top and bottom corner plates together, and at the same time stiffen and strengthen the joint between the side and end members of the crate.

By preference, the rigid engagement of the rod 17 with the plates 14 and 15 is effected by riveting the ends of said rod into countersunk seats in the plates, as shown in Fig. 9, although other means of effecting such engagement may be used, if desired.

The bottom plate 15 is let into a mortise 18 somewhat deeper than the thickness of the plate so that, if the lower end of the rod 17 projects beyond the face of the plate 15, it will not project beyond the bottom face of the crate and will not, therefore, interfere with the smooth travel of the crate over a roller bed or other supporting surface. 60

I claim:

1. The combination of the end members of a bottle crate with a bottle separator having longitudinal members whose ends are secured to said end members of the crate, each of said longitudinal members of the separator consisting of a flat strip which, at its ends, merges into a circular cross section having its axis in line with the body of the strip, said end portions passing through openings in the end members of the crate and being expanded at their outer ends. 65

2. The combination of the end members of a bottle crate, each of said members having therein transverse openings each with a 70 countersunk outer end having a washer bearing against the base thereof, with a bottle separator having longitudinal members, each consisting of a flat strip which, at the ends, merges into a circular cross section 75 having its axis in line with the body of the strip, said end portions passing through the transverse openings in the end members of the crate and being expanded at the outer ends so as to bear against the outer faces 80 of the washers at the base of the countersunk ends of said transverse openings.

3. The combination of the end members of the bottle crate with a bottle separator having longitudinal members whose ends are secured to the end members of the crate, each of said longitudinal members of the separator consisting of a flat strip which, at each end, has its edges curled upwardly and inwardly so as to present a split tubular 95 cross section having its axis in line with the body of the strip, said split tubular end portions passing through openings in the end members of the crate and each being expanded at its outer end to form a retaining 100 flange at right angles to its axis.

In testimony whereof, I have signed my name to this specification.

AMOS L. FOREMAN.
